UNITED STATES PATENT OFFICE.

CLARENCE H. HAPGOOD, OF DAYTON, OHIO, ASSIGNOR OF ONE-HALF TO
ENOCH FRY, OF SAME PLACE.

JIG-SAW.

SPECIFICATION forming part of Letters Patent No. 684,756, dated October 15, 1901.

Application filed June 27, 1901. Serial No. 66,265. (No model.)

To all whom it may concern:

Be it known that I, CLARENCE H. HAPGOOD, a citizen of the United States, residing at Dayton, in the county of Montgomery and State 5 of Ohio, have invented certain new and useful Improvements in Jig-Saws; and I do declare the following to be a full, clear, and exact description of the invention, such as will enable others skilled in the art to which it 10 appertains to make and use the same, reference being had to the accompanying drawings, and to the letters of reference marked thereon, which form a part of this specification.

15 This invention relates to improvements in jig-saws.

The object of the invention is to provide a saw of the above type in which the friction incidental to the operation of the saw is reduced to the lowest minimum, so that the 20 saw, if required, may be run by foot-power.

The object of the invention is to also provide means for holding the saw in perfect alinement, so that the cross-cut, miter, and 25 rip work can be done with accuracy by means of gages.

A further object of the invention is to combine means for sawing scrollwork, cross-cut, miter, and rip work in a single machine, all 30 of which will be hereinafter more fully described.

Preceding a detail description of my invention, reference is made to the accompanying drawings, of which—

35 Figure 1 is a side elevation of my improved jig-saw, the table being shown in section. Fig. 2 is a top plan view of the table, the mechanism below the table appearing in dotted lines. Fig. 3 is a view of the frame and table looking in the direction of the arrow in Fig. 1, the saw and saw-beams being detached. Fig. 4 is an enlarged section of the beam-stand and pivots on the line $x'x$ of Fig. 1, a portion of the beam-stand being broken out.

40 Fig. 5 is a side elevation of the beam-stand, a portion of which is broken out. Fig. 6 is a sectional elevation of the forward end of the upper beam, showing the manner of its connection with the saw. Fig. 7 is a side elevation of the upper end of the beam-stand, showing its connection with the upper beam. Fig.

8 is a side elevation of the forward end of the upper beam and its saw-chuck. Fig. 9 is an elevation of the forward end of the lower beam, showing its saw-chuck and bracket or cap. 55 Fig. 10 is an elevation of the rear end of the upper beam, showing its pivot connection with the turnbuckle. Fig. 11 is a front end view of the upper beam, saw-chuck, and bracket or cap. Fig. 12 is a sectional view on the line $y'y$ 60 of Fig. 2. Fig. 13 is an elevation of the power-transmitting devices, showing the lower beam in section. Fig. 14 is a plan view of the under side of the antifriction saw-alining devices. Fig. 15 is a section view thereof on the line $x'x'$ 65 of Fig. 14. Fig. 16 is a top plan view of the same.

In a detail description of my invention similar reference characters indicate corresponding parts.

A designates a suitable upright frame having connected thereto or being an integral part thereof a rearward bracket A'', which affords a support for the beam-stand B, to be again referred to. The table A' has in its 75 top side openings V' and V'', which form guides for gages Z and Y; also, a rectangular opening V''' in which the frame C of the saw-alining devices is placed. These devices will be again referred to.

E designates a spider which supports a driving-shaft C' of fly-wheel D, the said spider being attached to the right-hand side of the frame.

E' is a crank-hanger which is connected to 85 a foot-treadle F by a pitman G.

H is a belt driven from the fly-wheel D and passing around a small pulley I on a counter-shaft J, said counter-shaft J having a bearing in a hanger K, attached to the upper portion 90 of the frame. Thus power is transmitted to the lower saw-beam O. The counter-shaft J has no lateral or longitudinal movement.

L designates a small fly-wheel on the counter-shaft J. Projecting from this fly-wheel 95 is a wrist-pin m, which enters a slot N in a bracket N', which extends forwardly and supports knife-edge pivot h'. This bracket is secured to the lower beam O. Collars o o are fast on the wrist-pin and inclose the sides of 100 the bracket N' and prevent any side or lateral movement of the beam O. The upper

beam O' and the lower beam O are connected to the beam-stand B and have their fulerums on knife-edge pivots p p' , the former of which projects downwardly into a V-shaped bearing q and the latter of which projects upwardly into a V-shaped bearing q' . The said pivots pass through the beams and through clips P P' on said beams. (See Figs. 4, 5, and 7.) The ends of said pivots p p' are tapered, so as to provide points r , which are inclosed by plates s , which are secured to the beam-stand B . The said tapering ends of said pivots form an antifriction-bearing at the center of the motion of the beams, whereby any lateral movement of said beams is prevented with the least possible friction.

S S' are knife-edge pivots in the rear ends of the beams, in which position they are clamped by bolts c . The ends of said beams are slotted at c' , and the screws or bolts c clamp said slotted ends in rigid contact with said knife-edge pivots. These pivots S S' oscillate in V-shape bearings R R' in loops which are connected by a turnbuckle R'' , by means of which proper adjustments of the beams are had.

d is a metal cap which is secured to the forward end of the upper beam O' to provide a bearing for the knife-edge pivot d' , through which it passes.

d'' is a saw-chuck which has a V-shape bearing d''' on each side of the cap d and in which the knife-edge pivot d' oscillates.

The knife-edge pivots p p' are limited in any movement away from their bearings q q' by blocks q'' , which are placed on the beam-stand immediately above and below said pivots, with some intervening space, so as not to interfere with the necessary oscillations of said pivots. (See Fig. 5.)

e is a saw which has a semicircular notch e' in each end which receive the screws f , which secure the ends of the saw between the upper saw-chuck d'' and the lower saw-chuck h . By providing the ends of the saw with these notches e' the said saw is more easily placed in a proper alinement with the chucks d'' and h . The lower chuck h provides an open V-shaped bearing h'' for the knife-edge pivot h' . The knife-edge of the upper pivot d' projects upwardly, while the knife-edge of the pivot h' projects downwardly. It will be understood that all of the knife-edge pivots of the upper beam O' , with the exception of fulcrum-pivot p , project upwardly, while those of the lower beam O , with the exception of fulcrum-pivot p' , project downwardly.

C designates the metallic frame hereinbefore referred to, which is secured to the table A' within the slot V''' . This frame has pivoted in the opening therein a plate M , which is hinged or pivoted to said frame by means of a rod M' , journaled in bosses L' on the frame. t are two sliding pieces which move in ways t' on the under side of said plate M . Each of these plates has an oblong slot t'' therein, through which broad-headed screws u pass

and permit of adjustments of the said plates from or toward each other. The plate M has a slot n , through which the saw e passes. The inner adjacent ends of the plates t have mounted therein antifriction-rollers n' , which form roller-guides to maintain the saw in proper alinement immediately below the surface of the table. Proper contact of the rollers n' with the opposite sides of the saw is obtained by adjusting the pieces t , after which said plates are secured in such adjusted position by means of the screws u , as before described. The plate M is locked in position by a screw a' , which passes through an opening b' , which is partially within a side of the frame C and the adjacent edge of the plate M , as is shown in Fig. 16. The head of this screw a' is cut away at a'' , but the rounded portion of said head projects over the edge of the plate M when it is desired to hold said plate in a lower position, as is shown in Figs. 14 and 16. These views show the device when it is desired to cut miters, rip work, or, in fact, any work other than scrollwork. When it is desirable to perform the latter work, the plate M is unlocked by turning the screw a' to bring the straight edge a'' thereof in line with the adjacent edge of the plate M , after which the said plate may be turned upwardly on its hinge M' , thus removing the rollers n' away from the saw and allowing said saw the necessary space for scrollwork.

Referring to Fig. 2, Z designates a gage which fits in the dovetail slot V' and is movable to and from a side of the saw. Z' is a thumb-screw which enters a dovetail wedge Z'' , which lies within the dovetail slot V' . By turning this thumb-screw in one direction it releases the connection and permits of longitudinal adjustments of the gage Z , while in turning it in the opposite direction the said gage is fixed in its adjusted position. Y is another gage movable to and from the cutting edge of the saw in the dovetail slot V'' . The adjustment of this gage is through a thumb-screw Y' , similar to the manner of adjusting and securing the gage Z .

Having described my invention, I claim—

1. In a jig-saw, the combination of upper and lower beams, a beam-stand, knife-edge pivots connecting the beams with said stand, the said pivots having the ends thereof beveled so as to avoid undue friction in checking any lateral movement of the beams, and friction-plates inclosing said beveled ends of the pivots, substantially as specified.

2. In a jig-saw, the combination of upper and lower beams, a beam-stand, knife-edge pivots connecting the beams to the beam-stand, knife-edge pivots connected to the forward ends of said beams, saw-chucks having V-shaped bearings by which they are connected to said pivots, the saw-chuck of the lower beam being open so as to admit of detachment from the beam, a saw clamped to said chucks, knife-edge pivots secured to the

rear ends of the beams, and a turnbuckle by means of which proper adjustments of the beams are obtained.

3. In a jig-saw, the combination of an upper and lower beam, a beam-stand upon which the said beams are fulcrumed, the said fulcrums being knife-edge pivots, and the said pivots having their ends tapered, friction-plates secured to the beam-stand and inclosing said tapered ends of said pivots, knife-edge pivots at the rear ends of said beams, a turnbuckle connected to said pivots, knife-edge pivots at the forward end of said beams, a saw, and saw-chucks forming connections between said knife-edge pivots and said saw, all arranged substantially as specified.

4. In a jig-saw, the combination of saw-beams, a beam-stand, said beams being fulcrumed on said stand on knife-edge pivots, the fulcrum-pivots having their ends tapered and inclosed by friction-plates whereby any undue lateral movement of the beams is checked without undue friction, an adjusting device connecting the rear ends of the beams by knife-edge pivots secured to the forward ends of the beams, saw-chucks, each of which forms a clamp for the saw, and a V-shaped bearing for its respective knife-pivot, a saw

connected to said beams by means of said knife-edge pivots and chucks, and antifriction guide devices inclosing opposite sides of said saw and maintaining it in proper alignment during the operation thereof.

5. In a jig-saw, the combination of the beams, three knife-edge pivots connecting said beams, the intervening pivot of each beam forming the main fulcrum of such beam, the knife-edge pivots adjacent to said fulcrums being connected by adjusting devices for said beams, and the knife-edge pivots at the forward ends of the beams forming the saw connections of said beams, a cap or bracket secured to the forward end of the lower beam the same forming a support for the lower knife-edge pivot, and also having an oblong opening N therein, a wrist-pin projected into said opening, and means connecting said wrist-pin with the power-supplying mechanism, all arranged substantially as specified.

In testimony whereof I affix my signature in presence of two witnesses.

CLARENCE H. HAPGOOD.
